(57) **CLAIM**

The ornamental design for a snack box as shown and described.

DESCRIPTION

FIG. 1 is a perspective view of a snack box showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof, shown with the top lid handle in extended condition.

The broken lines in the drawings depict portions of the snack box that form no part of the claimed design.

1 Claim, 8 Drawing Sheets
